[57] CLAIM

The ornamental design for a portion of a shoe upper, as shown and described.

DESCRIPTION

FIG. 1 is a perspective view of a portion of a shoe upper showing my new design;

FIG. 2 is a left side view thereof;

FIG. 3 is a right side view thereof; and,

FIG. 4 is a top plan view thereof.

The uneven broken line showing of the perforations at the ends of the claimed region of the shoe is for illustrative purposes only and form no part of the claimed design.
